FIG. 1

FIG. 2

FIG. 3

FIG. 4

FIG. 5

FIG. 6

FIG. 7

Figure 1 is a side perspective view of a phonograph stylus and holder therefor or similar article, showing my new design;

Figures 2, 3 and 4 are end sectional views taken along the section lines II-II, III-III and IV-IV of Figure 1;

Figure 6 is a right side elevation thereof, a portion of the stylus being deleted therefrom for convenience of illustration; and

The dominant features of my design reside in the portions shown in full lines.

I claim:

The ornamental design for a phonograph stylus and holder therefor or similar article, as shown and described.
